UNITED STATES PATENT OFFICE.

FRANK P. TUTTLE, OF INDIANAPOLIS, INDIANA, ASSIGNOR TO THE CLEVELAND OSBORN MANUFACTURING COMPANY, OF CLEVELAND, OHIO, A CORPORATION OF OHIO.

BRUSHING OR POLISHING APPARATUS.

1,391,221.

Specification of Letters Patent. Patented Sept. 20, 1921.

Application filed August 14, 1918. Serial No. 249,856.

To all whom it may concern:

Be it known that I, FRANK P. TUTTLE, a citizen of the United States, residing at Indianapolis, in the county of Marion and State of Indiana, have invented a new and useful Improvement in Brushing or Polishing Apparatus, of which the following is a specification, reference being had to the accompanying drawings, and to the letters and figures of reference marked thereon.

This invention relates to apparatus adapted to be operated by a portable motor to be carried by the operator for performing various operations on various different objects, such as pieces of machinery, the invention having reference more particularly to apparatus for cleaning castings or brushing or polishing generally.

An object of the invention is to provide apparatus which shall be so constructed as to be adapted to be connected with an electric motor or a pneumatic motor and to be operated thereby, which apparatus shall be adapted to carry and operate various types of brushing or polishing devices.

Another object is to provide an improved brush and means for operating it and which shall be adapted for brushing and cleaning either convex surfaces or concave surfaces and also flat surfaces, such as variously curved surfaces of machinery castings.

A further object is to provide an improved brush which shall be adapted for brushing and cleaning surfaces in narrow openings or elsewhere requiring a thin brush.

With the above-mentioned and other objects in view, the invention consists in novel apparatus and appliances including a novel wire brush and holder therefor, and an improved machine for operating the brush or other brushes or devices; and, the invention consists also further in the parts and combinations and arrangements of parts as hereinafter particularly described and further defined in the accompanying claims.

Referring to the drawings,—Figure 1 is a side view of the improved brushing machine connected with an electric motor of familiar construction; Fig. 2 is a front end

elevation of the brushing machine; Fig. 3 is a side view of the improved machine having a polishing wheel connected thereto; Fig. 4 is a rear end view of the improved machine minus the brush or polishing device; Fig. 5 is a longitudinal central sectional view of the improved machine connected with portions of the motor; and, Fig. 6 is a fragmentary section of the improved machine provided with a modified form of brush.

Similar reference characters in the different figures of the drawings indicate corresponding elements or features of construction herein referred to.

The improved machine with slight variation of shape of its supporting frame may be adapted to be connected with various patterns of portable motors, an example of which is illustrated for descriptive purposes, the numeral 1 indicating an electric motor having a handle 2 on one end and a frame extension 3 on the opposite end thereof; the extension having a collar 4 beyond which projects an annular bearing portion 5, a spindle 6 extending from the motor through the extension 3 and having a reduced stud portion 7 extending from a shoulder 8, the stud portion having a screw 9 thereon, so that the spindle is adapted to carry drill chucks or various other tools.

The improved machine comprises a main frame portion 10 having a cylindrical base portion 11 thereon which is of suitable diameter to embrace the bearing portion 5 which is received into a bore 12 therein. The base portion 11 has a slot 13 and ears 14 and 15 adjacent to the slot and provided with a binding screw 16, for securely clamping the base portion 11 on the bearing portion 5. The main portion 10 is hollow and receives the projecting portion of the spindle 6 and preferably has slots 17 in its side. The main portion 10 has a spindle head 18 thereon which has a lateral arm 19 adjacent to its end, and the arm has a frame head 20 thereon that extends parallel with respect to the longitudinal axis of the frame portion 18 which rotatably carries a spindle 21 having a flat end portion 22 whereby to rotate

the spindle. The spindle 21 is connected with the spindle 6 by means of a coupler 23 which is cylindrical and has a socket bore 24 to receive the portion 7 while seated 5 against the shoulder 8 of the spindle 6. The coupler has also a bore 25 extending from the socket bore and having screw threads 26 therein to engage the screw 9, a slot 27 extending from the bore 25 to receive the flat 10 portion 22 whereby to rotate the spindle 21. A bevel gear 28 is secured to the outer end of the spindle 21, the latter extending beyond the portion 18. Preferably the frame 15 portion of the machine is composed of aluminum alloy so as to be of light weight.

The frame head 20 preferably comprises a bearing box or bushing 29. A bevel gear 30 is arranged in mesh with the gear 28 and it has a hub 31 thereon arranged rotatably 20 in the bearing box 29, being sufficiently long to extend through the box and beyond a bearing collar 32 secured in place, and also through a ball bearing case 33 containing bearing balls 34 which are arranged against 25 the collar 32. The hub 31 has screw threads 35 therein engaged by a screw shank 36 which has a collar 37 thereon and a screw threaded axle stud 38 extending beyond the collar. The collar is seated against the end 30 of the hub 31 and bears against the bearing rollers 34, so that the gear 30 and its hub may be easily rotated by means of the gear 28.

A novel brush and brush holder are provided in order to enable the machine to work 35 on a variety of different surfaces without requiring the brush to be changed. The brush holder comprises a cup having a bottom 39 that receives the stud 38 and is seated on the collar 37, and a flaring side wall 40 extending from the bottom 39. The holder comprises also a core 41 which has a tapering periphery 42 corresponding approximately to the shape of the wall 40 of 45 the cup but is less in diameter than the wall and has a groove 43 in the smaller portion of the periphery. The core is adapted to constitute a nut and is screwed onto the stud 38. Brush wires 44, corresponding to brush 50 bristles or "hairs" are provided and strung on a ring 45, the ring being placed in the groove 43 while the brush wires extend thence between the wall 40 and the periphery of the core 41.

55 When a thin brush is required instead of the cup-shaped brush, a flat collar 46 and a similar collar 47 are provided which have recesses 48 therein, the collars being placed on the stud 38 and secured in place by a nut 60 49 with one of the collars against the collar 37, brush wires 50 being arranged between the collars 46 and 47 and connected to a ring 51 arranged in the recess 48.

When neither of the brushes are used and 65 the machine is required for polishing pur-

poses a suitable polishing wheel or disk 52 is placed on the stud 38 against the collar 37 and secured in place preferably by means of a washer 53 and a nut 54 on the stud.

In practical use the apparatus is carried 70 by hand and operated or driven by the motor with which the apparatus frame and spindle are connected. The brush or other instrument required to be used is moved about on the surfaces requiring treatment. The 75 cup shape brush is especially useful for cleaning the inside surfaces of frame castings or casings, especially for working into corners. When rough surfaces are found they may be smoothed off by means of any 80 suitable grinding wheel. When polishing is required a polishing or buffing wheel is applied to the axle stud 38. The operator will find a large number of jobs which may be 85 advantageously done by means of this angle geared machine, without further explanation of its advantages.

Having thus described the invention, what is claimed as new is—

1. In a brushing or polishing apparatus, a 90 brush holder comprising a flat bottom and a flaring side wall thereon, a screw-threaded axle stud extending through said bottom from the rear side thereof, said stud having a collar thereon against said rear side and having also an operating shank extending from the collar, and a core screwed onto said stud and having a groove in its peripheral portion adjacent to said bottom, the front portion of said core having a greater 95 diameter than the grooved portion of the core, in combination with a brush between said sidewall and said core and having a portion arranged in said groove.

2. In a brushing or polishing apparatus, a 105 frame comprising a cylindrical base portion adapted to embrace a bearing portion of a motor frame, said base portion having a slot in its wall and also ears on opposite sides of the slot, a hollow main frame portion extending from said base portion and having a lateral arm adjacent to the end thereof, a head on said arm that extends parallel relatively to the longitudinal axis of said main frame portion, a bearing box in said head, and a bolt connected to said ears, in combination with a polishing device mounted on said head, and a rotatable shaft mounted in said main frame portion in operative connection with the polishing device.

110 3. In a brushing or polishing apparatus, the combination of a frame comprising a supporting base, a main frame portion on the base, a spindle head on said frame, a lateral arm on said spindle head, a frame 115 head on said arm, a bushing secured in said frame head, and a bearing collar secured to said bushing against said frame head; a gear having a hollow hub rotatable in said bushing and extending therethrough,

a ball bearing case extending about said hub adjacent to said bearing collar, bearing balls in said case to operate on said collar, a shank detachably secured in said hub and 5 having a collar thereon to operate on said balls, a threaded axle stud on said shank beyond the collar thereon, a brush on said stud, a spindle rotatable in said spindle head, and a driving pinion on said spindle in mesh with said gear. ¹⁰
In testimony whereof, I affix my signature in presence of two witnesses.

FRANK P. TUTTLE.
